Attorney.

UNITED STATES PATENT OFFICE

100,710

DESIGN FOR A CIRCULATION HEATER

Luke O. Morin, Jr., Chattanooga, Tenn.

Application March 31, 1936, Serial No. 61,875

Term of patent 7 years

To all whom it may concern:

Be it known that I, Luke O. Morin, Jr., a citizen of the United States, residing at Chattanooga, in the county of Hamilton and State of Tennessee, have invented a new, original, and ornamental Design for a Circulation Heater, of which the following is a specification, reference being had to the accompanying drawing, forming part thereof.

The figure is a perspective view of a circulation heater, showing my new design. The side of the heater not shown in the drawing is substantially the same as that of the side shown.

I claim:

The ornamental design for a circulation heater, as shown and described.

LUKE O. MORIN, JR.
